WASHING MACHINE IMPELLER

Alpheus W. Altorfer, Peoria, Ill.

Application July 19, 1933, Serial No. 681,096

8 Claims. (Cl. 259—101)

This invention relates to washing machine agitator impellers and the operation thereof to produce a peculiar water action for the purpose of washing clothes.

One object of the invention is to provide an agitating impeller having a form adapted to produce, when the impeller is operated in a washing machine tub, in the presence of water and clothing, a peculiar water action which will be described.

Another object is to provide an impeller which, when suitably operated in the presence of water and clothing, will produce a water action capable of thoroughly and uniformly agitating the clothing in the water to the end that the clothing will be thoroughly washed in a minimum of time, at the expense of a minimum amount of power.

A further object is to provide a water action which will thoroughly agitate and wash clothing with a minimum wear and damage thereto.

A still further object is to provide an impeller, the action of which, in the presence of water, will agitate and circulate the water in such a manner that clothing placed therein will be efficiently agitated therein without tangling.

Yet a further object is to provide an impeller for washing machines which, when suitably operated in the presence of water and clothing, will produce circulation of water and agitation of clothing therein in such a manner that clothing may be quickly and thoroughly washed without damage or tangling.

Other objects will appear in the following description and accompanying drawings in which—

Fig. 1 is a plan view of a washing machine tub of rectangular form with cover removed showing my impeller installed therein;

Fig. 2 is a sectional side elevational view of the tub and impeller as the same might be viewed from line 2—2 in Fig. 1, showing the general arcuate form of the lower portion of the tub, also a method of supporting the impeller within the tub.

Fig. 3 is a plan view showing the tub in section as the same would appear with the lid and drain ring removed showing water action to be described;

Fig. 4 is an elevational cross-section through the tub taken on lines 4—4 in Fig. 3;

Fig. 5 is a view similar to that shown in Fig. 3, showing water and clothes action to be described;

Fig. 6 is a view similar to that shown in Fig. 4, showing water and clothes action to be described;

Fig. 7 is a view similar to that shown in Figs.

3 and 5, showing my impeller as installed in a circular tub, also water action to be described;

Fig. 8 is a view similar to that shown in Figs. 4 and 6, showing the general form of the lower portion of the circular tub together with water action to be described;

Fig. 9 is an end elevational view of my impeller;

Fig. 10 is a side elevational view of the same;

Fig. 11 is a plan view of the same;

Fig. 12 is a plan view of the same as seen from below;

Fig. 13 is a sectional side elevational view of the same taken from line 13—13 in Fig. 9;

Figs. 14, 15, 16, 17 and 18 are views similar to those shown in Figs. 9, 10, 11, 12 and 13, showing a slight modification in the form of impeller surfaces to be described.

The impeller will first be described, but before proceeding with the description, it is in order to state that the proportions given are approximate and used only to facilitate illustration. Obviously, they may be altered to a considerable extent without departure from the general idea of the invention and without appreciable difference in the operation thereof or results obtained therefrom.

Proceeding with the description, Fig. 11 will indicate that the impeller has a circular base form, the periphery of which is designated as 10, while the horizontal base line is designated as 11.

For the purpose of convenient description, the radius of circle 10 divided by one hundred will be considered a comparative unit by which the proportionate form of the several portions of the impeller may be described.

As indicated in Fig. 9, continuous arcuate surfaces 12 are formed and disposed upon either side of a diametrical center line of the impeller, the center of the circles of which surfaces 12 are a part being disposed parallel with each other and with the plane of the base circle 10.

The curvature of surfaces 12 is such as may have a radius of seventy-eight units, or seventy-eight one-hundredths of the radius of circle 10, about centers disposed ninety units above base line 11 and ninety-three units either side of center line of the impeller.

The upper portion of surfaces 12 follows reverse curves as 13, which meet to form the upper line 14 as shown in Fig. 10, the general line of surfaces 12, as viewed in Fig. 10, following a curve 14', having a radius of approximately forty units, to meet a line 14'' projected perpendicularly to base line 11, from peripheral line 10.

- Disposed upon either extremity of the upper portion of surfaces 12 are extended shoulder or lobular portions 15 having cross-sections of arcuate form having a radius of approximately seven units, and peripheries, as viewed in Fig. 10, formed upon a radius of approximately thirty-three units, the said peripheries being so disposed as to pass through or near points of intersection of lines projected upon lines 14 and 14''.
10. The upper side of peripheries 15 follows the curve of the radius mentioned to extend the said peripheries toward the center of the impeller to meet line 14 at a point approximately intermediate the center of impeller and point of intersection of extended lines 14 and 14'' already mentioned.
15. The outer line of peripheries 15 follows the curve of radius mentioned outwardly and downwardly to a point where a tangential line projected therefrom will meet the lower circle 10 adjacent base line 11 is clearly shown in Fig. 13.
20. Extending upwardly at the center of the impeller is a tubular column portion 16 which is shown in section in Figs. 2 and 13. Secured 25 within the upper end of column 16 is a bushing member 17 having a rectangular opening, as shown in Fig. 12.
25. Secured to the under side of the lower portions 30 of the body of surfaces 12, as shown in Fig. 12, is a spider bracket member 18 having at its center a bossed portion within which an opening 19 is formed.
30. Reference to Fig. 2 will indicate that any tub, such as 20, may have secured at its bottom center 35 a column member 21, which extends upwardly within the tub to a point above the normal water line, which is here designated as 22.
35. Rotatably mounted within column 21 is a shaft member 23 having its upper end so formed as to fit within the rectangular opening of bushing 17 of column 16.
40. Reference to Fig. 2 will indicate that the impeller is adapted to be rotatably supported within tub 20 by means of the column 21, the lower portion 45 of the impeller being supported by means of the opening 19 of bracket 18 surrounding the lower portion of column 21, the upper portion retained in suitable alignment by means of the upper end of shaft 23.
45. For the purpose of illustration, it may be assumed that shaft 23 is connected with driving means by which the shaft, together with the impeller, is rotated in an oscillatory manner through approximately 180 degrees.
50. The rotating movement may be arranged to begin at any point and for convenience is here shown as beginning where shoulders 15 are shown in dotted lines in Figs. 3 and 5, the position being designated by A-A'. In operation, the speed of rotation accelerates to a point midway between positions A and A', which position is shown in solid lines in Figs. 3 and 5, and designated B-B. After position B-B has been passed, the rotational speed decreases to zero at position A'. Reverse movement then begins, following the course just described.
55. Assuming the impeller to be immersed in water to a depth approximately indicated by line 22 in Fig. 4, when the above described oscillatory rotation takes place, the resulting movement of water will be substantially as follows:
60. In Figs. 3 and 4 major and minor currents are indicated by arrows, those in Fig. 4 designated as M and E, F and G respectively. It will be clear that the centrifugal action of the rotating

impeller will tend to set up a radial movement of water, the movement being greatest when the impeller is rotating at its highest speed, which takes place, as already noted, when the impeller wings are passing positions B-B. This movement gives rise to the major currents shown at M. The currents M leaving the impeller are deflected upwardly by the sides of the tub to ripple the surface of the water. Simultaneously with the described outward and upward flow of water, a replacement flow near the central column 16 takes place, the overall effect being, with modifications to be noted, a circulation of water outwardly from the peripheral ends of the impeller, upwardly along the sides of the tub, inwardly at the surface level to center column 16 and downwardly to replace the outflow just mentioned. The foregoing has described the major currents M.

The current M is modified somewhat by a flow 20 of water which is induced by the scoop-like action of the advancing portions of surfaces 12. A portion of the water thus moved passes rapidly around and adjacent shoulders 15 for replacement at the receding side, which movement will be 25 again referred to, while another portion is induced to flow upwardly and away from shoulders 15, these currents being indicated by arrows E, F and G in Fig. 9. This vertical movement is influenced by centrifugal action in such a manner 30 that the water tends to leave the impeller flowing in an upward and outward direction to join, and be deflected inwardly by, the major stream M as indicated in Fig. 4.

The foregoing has described the minor currents E, F and G, as modifying, and modified by, the major currents M.

As already noted, the impeller rotates in an oscillatory manner through approximately 180 degrees. Referring to Fig. 3, the point of greatest 40 rotational speed and hence greatest activity of water as recently described, is indicated by solid outline of shoulders 15 and designated B, B, while the point of stop and reversal is indicated by dotted outline and designated A-A'.

Arrows in Fig. 3 indicate the predominating flow, at the surface, of currents M. The peculiar formation indicated is explained as follows:

As already noted, the speed of rotation of the impeller increases from zero at reversing position A-A' to maximum at position B-B and thence decreases to zero at position A-A'. Therefore, the activity of currents M and E, F and G is greatest in the vicinity of position B-B of the impeller and least in vicinity of position A-A', the activity at points between the extremes varying approximately as the rotational speed of the impeller.

Due to the described localized activity, four zones of activity are formed about the impeller, 60 two lying at opposite sides of the impeller adjacent the line of B-B position and having more clearly defined circulation currents as M-E, F, G, and two lying at opposite sides of the impeller adjacent the line A-A' position wherein 65 the water is highly agitated, due to the stop and reverse movement of the impeller, but has little or no definite circulating movement.

It may be noted here that the zones just mentioned are formed and disposed within the tub 70 entirely by the impeller action, the form of tub having no effect upon the relative position of zones of activity. Fig. 3, referred to in the foregoing description, shows the impeller as operating in a rectangular tub with zones of activity dis- 75

posed in the corners thereof, however, the location of zones is determined by the line upon which the impeller reverses. In the case of Fig. 3, had the reversing line A—A' passed through the sides 5 of the tub, the zones would have been correspondingly disposed at the sides of the tub.

Fig. 7 will indicate the action as taking place in a round tub wherein the zones are clearly defined as lying upon the reversing and intermediate 10 lines A—A' and B—B, as in the case just described.

The foregoing has described the action of the impeller when immersed in water.

Clothes suspended in the water tend to modify 15 the described currents somewhat, without, however, appreciably altering the predominating actions or formation and disposition of zones described.

Arrows shown in Fig. 6, indicate that, with 20 clothes suspended in the water, the major circulating current M is well defined, while the formerly described minor current E, F, G, is substantially absent. This modification may be explained as follows:

25 Clothes suspended in the water are induced by current M to generally move along the line thereof, as shown; however, the agitative action set up in the vicinity of shoulders 15 tends to interfere with this more or less orderly movement to 30 such an extent that the clothes, while generally following the line M as described, are induced to pause in the area designated as C, in Fig. 6, where they are subjected to active agitation, as will be later explained.

35 The presence of clothes in the water alters the disposition and form of the zones of activity described, only to the extent that the nuclear localizations of the zones of line B—B are so modified as to increase the area of zones B—B somewhat 40 and correspondingly decrease the area of zones A—A', the difference being indicated by arrows in Figs. 3 and 5.

Clothes introduced into the water in which the impeller is operating tend to occupy and remain 45 in the zones of line B—B, with a certain amount of interchange of clothes between zones. However, the overall action of the impeller, when operating in water containing clothes, is to separate the clothes to cause them to generally occupy 50 the zones of line B—B, with a certain amount of interchange as described, and to circulate the clothes lying within each zone, generally along the lines M as described.

Referring specifically to the clothes-water action 55 taking place in the area generally designated as C in Fig. 6, also to arrows designated E, F and G in Fig. 9, it will be noted that an incidental water action takes place adjacent the shoulders 15 as follows:

60 Assuming the impeller to be rotating in the direction shown by arrow 24, and passing approximately across the line B—B, as already noted in connection with Fig. 3, a movement of water is induced as indicated by the arrows designated E, F and G, wherein a portion of the water displaced by the advancing surface 12 is shown as 65 passing over the surface of shoulder 15 and thence downwardly adjacent the receding side, as designated by E, while other portions, such as those designated F and G, follow the general direction of current E in progressively widening 70 circular paths.

Obviously, the flow generally designated by E, 75 as well as currents F and G, is induced by dis- placement on the advancing side, and replace-

ment on the receding side, of the impeller surfaces 12.

In the case of current E, water will tend to flow from a point on the advancing side to a similar point on the receding side.

A unit of water, in following the circuitous route around shoulders 15, will travel a greater distance than an adjacent point on the impeller, hence the velocity of current E, and accompanying currents F and G, as induced by the rapidly 10 moving impeller, will be comparatively high.

It will be noted that water movement indicated by the arrows E, F and G, as shown in Fig. 9, takes place in the space referred to as C in Fig. 6 and that this movement, as in Fig. 6, will approximately correspond to the currents E, F, G, illustrated in Fig. 4.

It will also be noted that these water currents flow in a general direction at right angles with the major current M.

The major stream M, being induced by centrifugal action as already explained, is urged to flow in the one general direction indicated, regardless of the direction of rotation of the impeller, while the currents E, F and G are reversed 25 as the rotation of the impeller is reversed. Thus the current M receives two impulses in the same direction at each cycle of operation of the impeller, while currents E, F, G, receive one impulse in each direction during the said cycle.

It will be quite apparent that the water movements described, as set up and maintained by a rapidly moving impeller, each current modifying and modified by the others, will be highly agitative.

35 Materials suspended in the water, especially those occupying the area C, Fig. 6, will be induced by currents E, F and G to follow the general direction thereof, which movement will tend to rapidly flex the body of the materials in such a manner as to expose all sides of the threads and fibres of the materials to the action of the rapidly moving surrounding water.

It has already been noted that clothing suspended in water in a tub in which my impeller 45 operates, tends to move in the general line of current M and to pause in the area generally designated by C, where it is subjected to the action of currents E, F and G, as more recently described.

50 It will be apparent that the described impeller and water action produced thereby forms a highly efficient washing means.

Reference will now be made to Figs. 14, 15, 16, 17 and 18 wherein is shown a modification 55 of my impeller.

The several views will indicate that surfaces 12 may have formed therein a plurality of rib-like protruding portions, as 23, in the higher portion of which perforations 24 are provided, substantially as shown, the perforations communicating between the outer and inner portions of the impeller.

60 In operation, the movement of the impeller as modified, causes an additional agitation of water in the vicinity of surfaces 12, which agitation is caused by the flow of a certain amount of water in either direction through the perforations 24, also, clothing coming in contact with ribs 23 are subjected to a certain amount 65 of washboard action.

70 What I claim is:

75 1. An impeller having a circular base form, a central portion extending upwardly perpendicular thereto, parallel facial surfaces disposed

- upon opposite sides of the central portion, each formed upon an arcuate line extending from opposite edges of said base portion inwardly and upwardly toward the central portion, arcuate portions of comparatively small dimensions connecting the upper parts of the aforementioned parallel surfaces to form blunt ridges extending radially from opposite sides of said central portion to the peripheral line of said base portion, the ridges lying parallel with the base portion and disposed substantially above the latter shoulder portions disposed upon the outer portions of said ridges and extending upwardly and outwardly therefrom each beginning at a point intermediate the central portion and outer ends thereof and continuing toward and around the outer ends to a point between the base and line of said ridge, said shoulder portions having a rounded cross-sectional form of dimensions somewhat larger than those of said ridges.
2. An impeller as set forth in claim 1 having a hollow shell-like construction, the interior surfaces having contour similar to the external surfaces.
3. An impeller as set forth in claim 1, the said facial surfaces of which are provided with a plurality of elongated raised rib-like portions disposed circumferentially upon said surfaces the ribs having plural perforations, the perforations forming orifices communicating between the exterior and interior surfaces of the walls of said facial surfaces.
4. An impeller having a circular base form from opposite edges of which arcuate facial surfaces extend inwardly and upwardly toward a diametrical line of said base, said surfaces being joined at their upper extremities in such a manner that the joining portions form ridges, which ridges, together with said facial surfaces form wing-like portions extending radially upon opposite sides of the axial center of the circular base, the ridges being disposed at a point substantially above the said base, rounded shoulder portions of dimensions somewhat larger than those of the ridges, disposed thereupon and extending upwardly and outwardly therefrom beginning at a point intermediate the axial center line of the base and outer extremity of the ridges, continuing therefrom toward and about said extremities to a point substantially below the ridges, the impeller adapted to be immersed in fluid contained in a tub with the base portion of the impeller paralleling the bottom of the tub and to be rotated therein upon its axial center in an oscillatory manner through approximately 180 degrees, the described form of impeller, when so rotated, adapted to induce about either of the wing portions thereof, in vicinity of the reversing point of the impeller, turbulent, heterogeneous currents in the fluid and in the vicinity intermediate the reversing point, currents flowing radially outwardly from the described wing portions upwardly along the sides of the tub and inwardly toward the center of the impeller above the wing portions, currents flowing upwardly along the advancing side of the said facial surfaces a portion thereof flowing circuitously about the said shoulder portions, said radially flowing currents moving substantially in one direction regardless of the direction of rotation of the impeller, said upwardly flowing currents moving upwardly from opposite sides of said facial surfaces according to direction of rotation of the impeller, said circuitously flowing portions thereof moving in reverse directions as the direction of rotation of the impeller reverses, and substantially at right angles with said radially flowing currents a portion of the upwardly flowing currents joining and mingling with the radially flowing currents in the area above the wing portions.
5. An impeller as set forth in claim 4 having a hollow, shell-like construction, the interior surfaces having contour similar to the external surfaces.
6. An impeller as set forth in claim 1, the said arcuate facial surfaces of which are provided with a plurality of elongated raised rib-like portions disposed circumferentially upon said surfaces, the ribs having plural perforations, the perforations forming orifices through which fluid may flow between the exterior and interior portions of the impeller body.
7. An impeller having a circular base form, a central stem portion extending upwardly perpendicular thereto, facial surfaces disposed upon opposite sides of said stem portion each formed upon arcuate lines having parallel axes and extending from opposite edges of said base portion inwardly and upwardly toward the stem portion, arcuate portions of comparatively small dimensions connecting the upper parts of the aforementioned surfaces to form blunt ridge portions extending radially from opposite sides of said stem portion to the peripheral line of said base portion, the ridges lying parallel with the base portion and disposed substantially above the latter.
8. A washing machine impeller having a form produced by a cylinder having diameter equal to or less than its height, opposite walls of which are intersected by oppositely disposed concave surfaces formed about center lines lying parallel to each other and disposed on opposite sides of the axial center of the cylinder, a substantial distance therefrom, and parallel with the base plane thereof, the relative position of the aforementioned centers being such that said concave surfaces extend inwardly and upwardly from opposite sides of the lower portion of the cylinder to a point adjacent a diametrical line of the cylinder the upper edges of said concave surfaces being joined by an oppositely curved surface to form an elevated ridge across the cylinder and a vertical stem extending upwardly from the center of said ridge.

ALPHEUS W. ALTORFER.
